UNITED STATES PATENT OFFICE.

JAMES H. BLAKE, OF SEAMAN, OHIO.

LAMP-CHIMNEY HOLDER.

1,125,448.

Specification of Letters Patent.

Patented Jan. 19, 1915.

Application filed April 17, 1914. Serial No. 332,573.

To all whom it may concern:

Be it known that I, JAMES H. BLAKE, citizen of the United States, residing at Seaman, in the county of Adams and State of Ohio, have invented certain new and useful Improvements in Lamp-Chimney Holders, of which the following is a specification.

This invention relates to certain new and useful improvements in lamp chimney holders particularly adapted for use in connection with the ordinary kerosene lamp as now manufactured.

The invention has as its primary object to provide a holder which may be detachably connected to the burner of the lamp and so arranged as to engage the lamp chimney to securely hold it in position upon the burner.

A further object of the invention is to provide a lamp chimney holder so constructed and arranged as to automatically engage the lamp chimney upon the application of the chimney to the burner and so constructed as to resiliently engage the lamp chimney.

The invention has as a further object to provide a lamp chimney holder adapted to securely hold the chimney in place upon the burner and which may be readily engaged with or disengaged from the chimney. And a still further object of the invention is to provide a lamp chimney holder which will be simple in construction and thus capable of ready manufacture and which will at the same time be thoroughly efficient in operation.

With these and other objects in view my invention will be more fully described, illustrated in the accompanying drawings and then specifically pointed out in the claims which are attached to and form a part of this application.

In the accompanying drawings:—Figure 1 is a perspective view showing my improved lamp chimney holder applied to a lamp burner, the chimney being shown in section. Fig. 2 is a detail sectional view especially showing the shoulders formed on the lamp chimney, which shoulders are arranged to engage the holder, Fig. 3 is a detail perspective view of the holder, and Fig. 4 is a perspective view of a modified form of attaching means between the holder and the lamp chimney.

Corresponding and like parts are referred to in the following description and indicated in all the views of the drawings by the same reference characters.

My improved lamp chimney holder may be applied to any ordinary type of burner with but very little change in the construction thereof and in Fig. 1 of the drawings I have shown the holder as applied to a burner having the usual socket 10, base 11, and draft cone 12, there being the usual resilient fingers 13 arranged on the burner 65 and connected to the base thereof.

My improved holder may be constructed of any suitable material but is preferably formed from a length of suitable resilient sheet metal which is bent upon itself to provide a substantially semi-circular body portion 14. The body portion 14 may, however, if desired, be substantially U-shaped since in thus forming the holder, the efficiency thereof will not be impaired and I therefore 75 do not wish to limit myself to the specific configuration of the body portion of the holder which I have shown.

In further describing the body portion 14 of the holder, the free extremities thereof 80 will be designated as arms 15 which are joined by a preferably flat connecting portion 16. At their free extremities each of the arms 15 is bent laterally at substantially right angles to the adjacent portion of the 85 arm to provide an extension 17 upon each arm and formed on each of said extensions 17 at the free extremity thereof, is an up-standing or vertically disposed catch member 18, each of which is provided with outwardly facing shoulders 19. The upper outer edge of each of said catch members is preferably curved as shown at 20 for a reason which will be presently described.

The holder thus formed is connected to 95 the base 11 of the lamp burner preferably by a screw 21 which engages within a screw threaded opening 22 formed medially of the connecting portion 16 of the holder, and it will be observed that by flattening such connecting portion, the body portion of the holder is caused to lie flat against the base 100 of the burner.

The body portion of the holder is arranged exteriorly of the base of the burner 105 as shown in Fig. 1 of the drawing, which base is provided upon opposite sides with suitable transversely extending apertures through which the catch members 18 extend. As previously stated, the holder is formed 110 of resilient material and the arms 15 are so arranged that the shank 23 of each of the catch members 18 will be held when in normal position against the outer end wall of

each aperture. Secured to the arms 15 adjacent the outer extremities thereof are laterally disposed push rods or buttons 24 which are arranged to extend beneath the base 11 of the burner and are of such length as to project laterally upon each side thereof. As will be readily obvious, the catch members 18 may be easily actuated by compressing or releasing the said buttons.

10 The lamp chimney is designated at 25 and is provided with the usual base flange 26 which rests upon the burner 11 being engaged by the fingers 13. The base flange 26 is provided upon its interior face with 15 an annular flange 26' providing oppositely inclined shoulders 27 upon opposite sides of the flange 26, such shoulders being so arranged as to co-act with the catch members 18, being engaged by the shoulders thereof.

15 By this arrangement it will be seen that the chimney 25 may be thus held securely in position upon the burner and in this connection particular attention is directed to the arrangement and disposition of the shoulders 27. When placing the chimney upon the burner, said chimney may be so applied that the catch members 18 will pass over the flange 26' where it is depressed toward the outer edge of the flange 26. Then by rotating 20 the chimney in either direction the catch members 18 may be caused to engage the flange 26' medially of the oppositely inclined shoulders 27 upon each side of the chimney, the chimney being turned to a point where the base flange 26 will be held 25 tightly against the base of the burner. To disengage the chimney the push buttons 24 are provided.

In Fig. 4 of the drawings, I have shown 40 the base flange 26 of the chimney as being provided with suitable apertures 28, one of said apertures being provided upon each side of the base flange of the chimney and so arranged as to be engaged by the shoulders 45 19 of the catch members carried by the holder. In this form of the invention, the upper inclined edges 20 of the catch members will ride over the edges of the apertures, to thus easily engage therein and 50 when in such position the catch members will of course, be projected into said apertures to thus securely hold the chimney in position. It will also be observed that in the preferred form of the invention the 55 flange 26' will readily ride over the upper curved edges 20 of said catch members causing the catch members to be automatically sprung inwardly, said flange being preferably provided with an upwardly inclined 60 lower face 30 arranged to contact with the curved edges of said catch members.

It will therefore be seen that I provide a very simple and efficient structure for the

purpose set forth, such as may be readily applied and such as may be detached from 65 the burner as desired. It will also be seen that the holder is so arranged as to securely hold the lamp chimney in position upon the burner and is so disposed as to automatically engage the chimney upon application 70 thereof to the burner.

Having thus described my invention what I claim and desire to secure by Letters Patent is:—

1. A device of the character described including a lamp burner provided with a base having apertures formed therein upon opposite sides of the burner, a chimney holder detachably secured to the base, said holder including a substantially semi-circular body 80 portion arranged beneath the base, said body portion providing spaced resilient arms, upstanding catch members carried at the free extremity of said arms and arranged to project through the apertures formed in the 85 base, outwardly facing shoulders formed on said catch members, a lamp chimney formed with a base flange, and oppositely inclined shoulders arranged upon opposite sides of the interior face of the base flange of the 90 chimney and disposed to engage the shoulders of the catch members.

2. A device of the character described including a lamp burner, a chimney holder carried by the burner, said holder being 95 formed from a single piece of material bent to partially encircle the burner and having upstanding catch members integrally formed at its ends, the said catch members being provided with inwardly extending 100 horizontally arranged shoulders, a chimney, and means carried by the chimney and adapted to coact with the shoulders of said catch members to hold the chimney in position upon the burner.

3. A device of the character described including a lamp burner, a chimney holder carried by the burner, said holder being formed from a single length of material bent to partially encircle the burner, radially disposed extensions formed on said holder adjacent the extremities thereof, upstanding catch members carried at the outer ends of said extensions, the said catch members being disposed to engage a chimney, a 110 chimney, and means carried by the chimney and adapted to coact with said catch members to hold the chimney in position upon the burner.

In testimony whereof I affix my signature 120 in presence of two witnesses.

JAMES H. BLAKE. [L. S.]
